UNITED STATES PATENT OFFICE.

HARRY KENNEDY, OF BUFFALO, NEW YORK.

MUD-GUN.

1,332,298.

Specification of Letters Patent.

Patented Mar. 2, 1920.

Application filed April 26, 1918. Serial No. 230,982.

To all whom it may concern:

Be it known that I, HARRY KENNEDY, a resident of Buffalo, in the county of Erie and State of New York, have invented a new 5 and useful Improvement in Mud-Guns, of which the following is a specification.

This invention relates to mud guns for luting the tap holes in blast furnaces.

The object of the invention is to provide 10 a mounting for the gun which will permit easy positioning and adjustment thereof at various angles, and to provide means for elongating the gun after it is positioned and before discharge of the clay luting in order 15 to force the nose firmly into the tap hole of the furnace, or against the walls thereof, and to hold it firmly in that position.

Referring to the drawings, Figure 1 is a 20 plan view of one form of mud gun in operative position relative to the tap hole of a blast furnace; Fig. 2 is a partial central vertical longitudinal section through the gun; and Fig. 3 is a side elevation and partial section of the device mounted on a furnace.

25 On account of the great heat and gas pressure existing at the tap hole of blast furnaces, so-called "mud guns" are provided for luting the tap hole with plastic fire clay. These consist of cylinders, adapted to be 30 filled with the plastic fire clay, and having a piston mounted therein to force the mud out the open end, or nose, of the gun.

In use the nose of the mud gun is pushed 35 forward in the iron notch, or tap hole of the furnace and it is held there by some form of latch. Ordinarily this latch consists of locking extensions or levers situated near the forward end of the gun, connected to a shaft having a fixed position relative to the 40 furnace wall or supporting columns. This arrangement permits little or no adjustment of the gun in its horizontal and vertical planes, since the latches are ordinarily short and rigid. The result is that the nose of 45 the gun cannot be accurately positioned in the iron notch, or tap hole, and the pressure from within the furnace drives back the mud around the nose of the gun, so that a great deal of the luting is wasted. With 50 such devices frequently several discharges of the gun are necessary before the tap hole can be completely closed.

These difficulties are overcome by the device forming the subject of the present invention. In the drawings the tap hole H to be closed is shown in the wall F of a blast

furnace of ordinary construction. The device for closing said tap hole comprises a cylinder 2 closed at its outer end by a flanged head 3 and having leading thereto just inside said head a port 4 to which is connected a pipe 4^a leading to any suitable source of fluid pressure. The cylinder 2 is provided externally with longitudinal flanges 5 which are provided with a series 60 of holes 6 therethrough. A cylindrical member 7 having an enlarged head 8 acts as a piston in the chamber 9 of cylinder 2, the outward travel of said piston being limited by an internal annular shoulder 10 at the 65 open end of the cylinder 2—a suitable packing 11 being provided around the slide cylinder 7. The outer end of the member 7 is closed by a wall 13 to which is rigidly bolted a second and smaller cylinder 12, in 70 the chamber 15 of which is a piston 14. A port 16 leads into the chamber 15 and is connected by pipes 17 and 18 to any suitable source of fluid pressure. It will be understood that the pipe connections 4^a and 18 are 75 provided at some point in their lengths with a hose so that they are flexible. The piston 14 is connected by rod 19 to the clay ejecting piston or plunger 20 working in a cylinder 21 which is joined to the cylinder 12 by a 80 tapered reducing connection 21^a as shown in Fig. 3. Plastic fire clay is supplied to the cylinder 21 through charging opening 22 when the plunger 20 is retracted, and is forced out of the cylinder 21 through the 85 tapered nose piece or terminal nozzle 23 when said plunger is projected by the admission of fluid pressure into the chamber 15.

A jib crane 24 is supported by a vertical 90 shaft 25 and extensions 26 attached to a part of the furnace structure, such as column 27. From the outer end of this crane is rotatably suspended a yoke 28, the forks of which engage trunnions 29, on the sides of cylinder 12. This allows the nose piece 23 to be readily moved in the vertical plane and the swinging of the crane and swiveling of the yoke 28 permit free horizontal adjustment.

Cables 30 have hooks or loops at each end, which are adapted to be attached to the flanges 5 by engagement with one of the holes 6. The other ends of the cables are then attached to hooks 31 on upright beams 32, of the furnace structure. These cables 110 when attached form an abutment for the suspended gun. By changing the engage-

ment of the cables to different ones of holes 6, the distance of the mud gun from the furnace tap hole H may be varied, as will be apparent.

5. The operation of the device is as follows: The piston 14 being withdrawn to the wall 13, the cylinder 21 is filled with fire clay through port 22; the gun is swung into position so that the nose piece 23 rests in the 10 iron notch 33, and approximately in contact with the tap hole H. The cables 30 are then hooked to the girders 32 and to the gun, and fluid pressure is admitted by port 4 to chamber 9. This advances the cylinder 7 until 15 the nose piece 23 is forced firmly into the tap hole H, against pressure of the fluid material, and of the gas in the furnace. After this has been done, pressure in the cylinder 9 will hold the nose of the mud gun firmly 20 in position. Then fluid pressure is admitted through port 16 to the chamber 15. This drives the piston 14 and plunger 20, forcing the plastic clay through the nose piece 23 into the tap hole, effectively shutting off the 25 flow from the furnace and luting up the opening therein. When the clay has been discharged from the gun, pressure in chamber 9 is released, which permits ready removal of the mud gun for refilling and 30 use.

It will be understood that other pressure means for elongating the gun can be used, as a spring, a winding arrangement, screw, etc., but the fluid pressure is quicker and 35 more convenient.

The many advantages of this construction will be apparent to those familiar with the art.

I claim:

- 40 1. Means for closing the tap holes of blast furnaces, comprising a gun provided with a mud forcing piston and a fluid pressure actuating cylinder therefor, means movably supporting said gun, means to anchor the gun to an abutment, and means between the anchoring means and the actuating cylinder to elongate said gun.
- 45 2. Means for closing the tap holes of blast furnaces, comprising a gun provided with a mud forcing piston and a fluid pressure ac-

tuating cylinder therefor, means movably supporting said gun, means to anchor the gun to an abutment, and fluid pressure means between the anchoring means and actuating cylinder to elongate the gun.

55

3. Means for closing the tap holes of blast furnaces, comprising a mud gun provided with an actuating cylinder, a base member for said gun, means movably supporting said gun and base member, means to anchor the base member to an abutment, and an extensible connection between said base member and the gun actuating cylinder.

60

4. Means for closing the tap holes of blast furnaces, comprising a mud gun provided with an actuating cylinder, a base member for said gun, means movably supporting said gun and base member, means to anchor the base member to an abutment, and a member extensible by fluid pressure and connecting said base to the actuating cylinder.

65

5. Means for closing the tap holes of blast furnaces, comprising a fluid actuating mud gun, a base member therefor, means movably supporting said gun and base member, means for anchoring said base member at different distances from the tap hole, and a yieldable extensible connection between said base member and the gun.

70

6. Means for closing the tap holes of blast furnaces, comprising a fluid pressure gun, a base member therefor, means movably supporting said gun and base member, means for anchoring said base member at variable distances from the tap hole, and a fluid pressure extensible cylinder connecting the base member to said gun.

75

7. Means for closing the tap holes of blast furnaces, comprising a gun provided with a mud forcing piston and a fluid pressure actuating cylinder therefor, a swinging arm, flexible means for suspending said gun from said arm, means to anchor the gun to an abutment, and means between the anchoring means and the actuating cylinder to elongate said gun.

80

In testimony whereof I have hereunto set my hand.

HARRY KENNEDY.
